UNITED STATES PATENT OFFICE.

NORBERT F. KEMPEL, OF CHICAGO, ILLINOIS.

INDICATOR.

Application filed April 3, 1923. Serial No. 629,734.

To all whom it may concern:

Be it known that I, NORBERT F. KEMPEL, a citizen of the United States, residing at Chicago, in the county of Cook and State 5 of Illinois, have invented new and useful Improvements in Indicators, of which the following is a specification.

My invention relates to improvements in indicators and has special reference to devices used in connection with the water-cooling system of a motor vehicle.

The radiator, as is the case with all other parts of the water-cooling system of a motor vehicle, is subjected to considerable expansion 15 and contraction movement due to the varying pressure of steam within the radiator. These movements and stresses tend to disrupt the joints between the radiator and its tubes and ofttimes causes the bursting of a weak spot 20 in the radiator with resultant leakage, making it necessary to provide means to indicate and automatically relieve the dangerous steam pressure content of the cooling fluid.

The principal object of the invention is 25 to provide a device that will respond to the steam pressure within a radiator when said pressure closely approaches the safety factor used in the construction of a radiator.

A still further object of the invention is 30 to provide means whereby the pressure of the steam within a radiator or cooling system may be relieved at a predetermined period.

A still further object of the invention is 35 the simplicity in the construction and the decreased cost of manufacture which, together with the importance of a device of this character, tends to assure its commercial success.

With the above and other objects in view, as will be hereinafter apparent, the invention consists in general of certain novel important features, hereinafter fully described, and illustrated in the accompanying drawings, and the appended claims.

In the accompanying drawings, like characters of reference indicate similar parts in the several views of which:

Figure 1 is an elevation of the device in 50 its normal position, illustrating the means for attaching the same to a radiator cap;

Fig. 2 is an elevation of the device showing it in operative position;

Fig. 3 is a central vertical longitudinal 55 section through the device in its normal position, and

Fig. 4 is a similar view showing the device in operative position.

Generally speaking my device consists of a body portion 5, which is reduced in diameter at its lower end to form a screw-threaded shank 6 for insertion in an aperture in a radiator cap 7, whereupon a nut 8 is applied which securely supports the device in position. The said body portion 5 also 60 has a longitudinal bore 10 which terminates just short of the top of the former and is here provided with an axial aperture 11, the purpose of which will be hereinafter pointed out, and further, the said body portion 5 is reduced in diameter at its uppermost end, as indicated at 12, the shoulder 13 65 formed thereby being given a slight bevel, as clearly shown in Fig. 2.

Slidably mounted in the said longitudinal bore 10 is a reciprocatory plunger 14 which is carried by a vertical rod 15, the latter also supporting a bullet-shaped hood 16 at its upper end. The vertical rod 15 passes through the aperture 11, hereinbefore mentioned. 70

On reference to Fig. 3, it will be noted that said hood 16 is cored out, as indicated at 17, and also that the peripheral rim formed at the base of said hood 16 is given an upward bevel as indicated at 18. 75

It will thus be seen that when the device is in its normal position the reduced portion 12 extends up into the cored portion 17 of the hood 16, the peripheral rim of the latter resting on the beveled shoulder 13 of the 80 body portion 10.

The operation of the device will be readily understood on reference to Figs. 3 and 4. The steam in the radiator attaining more than the proper pressure forces the plunger 95 14 upwardly causing the hood 16 to rise and indicate to the operator of a motor vehicle that the steam in the radiator has reached the danger point. The hood 16 may be colored or given any distinctive marking 100 to better attract the attention of the operator.

In order to provide relief for abnormal steam pressure in the radiator I aperture the body portion to form a port 19. Thus 105 when the plunger 14 is forced to travel the entire length of the bore 10 and reaches its upward limitation by contacting with the top of the longitudinal bore 10, said port 19 establishes open communication between 110 the radiator and the atmosphere permitting the escape of steam until its pressure is

reduced and the plunger 14 drops downwardly closing the port 19 and cutting off the escape of steam. The hood 16 acts as a seal to prevent entrance of dirt into the aperture 19 when conditions are normal, and when there is an excess of steam within the radiator said cap 16 is elevated to act as a signal.

In accordance with the patent statutes, I have illustrated my invention in concrete form and as constructed in a specified manner, but it will be distinctly understood that I do not propose to limit myself to the precise structural detail set forth, since various modifications will immediately suggest themselves to those skilled in the art without departing from the spirit of my invention, the scope of which is set forth in the following claims.

Having thus described my invention, I claim as new and desire to secure by Letters Patent:

1. The combination with a radiator cap; of an indicator comprising a body portion having a longitudinal bore terminating just short of the top of the former, supporting means for said body portion, the body portion having a port communicating from said bore to the atmosphere, a closure member for said port embracing and sliding upon the outer surface of said body portion, and pressure responsive means within said body portion having an operative connection with said closure member.

2. The combination with a radiator cap; of an indicator comprising a body portion having a longitudinal bore terminating just short of the top of said body portion, the latter being diametrically reduced at its

uppermost portion and having a port communicating with said bore, a closure member receivable and guided upon said re-

duced uppermost portion of said body and functioning to normally close said port, a plunger capable of reciprocatory motion within said longitudinal bore actuated by the fluid pressure within the radiator, and an operative connection between said closure and the upper end of said plunger.

3. The combination with a radiator cap; of an indicator comprising a body portion having a longitudinal bore and an atmosphere communicating opening leading therefrom, a closure member for said opening guided upon the exterior of said body portion, and pressure responsive means within said bore having an operative connection with said closure member.

4. The combination with a radiator cap; of an indicator comprising a body portion having a recess therein in communication with the interior of the radiator and an atmosphere communicating port leading from said recess, a movable visual signal for normally closing said port when in non-signalling position, and means governed by the pressure within the radiator for actuating said visual signal from port closing to signalling position.

5. An indicator comprising a substantially hollow body portion open at one end and having an atmosphere communicating port leading through one wall thereof remote from said open end, a signal member carried by said body portion for normally closing said port when in non-signalling position, and pressure responsive means within said body portion having an operative connection with said signal member for moving the same from port closing to signalling position.

In testimony whereof I affix my signature.

NORBERT F. KEMPEL.
